(57) **CLAIM**

The ornamental design for oral care implement, as shown and described.

DESCRIPTION

FIG. 1 is a front right perspective view of a oral care implement according to a first embodiment of the new design;

FIG. 2 is a rear left perspective view thereof;

FIG. 3 is an enlarged front view thereof;

FIG. 4 is an enlarged rear view thereof;

FIG. 5 is an enlarged left side view thereof;

FIG. 6 is an enlarged right side view thereof;

FIG. 7 is an enlarged top view thereof;

FIG. 8 is an enlarged bottom view thereof;

FIG. 9 is a front right perspective view of a cleaning element portion for an oral care implement according to a second embodiment of the new design;

FIG. 10 is a rear left perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

The broken lines formed by even length segments shown in the drawings are for environmental structure only and form no part of the claimed design. The broken lines formed by dash dot dash lines define the bounds of the claimed design and form no part thereof.

1 Claim, 9 Drawing Sheets
